(57) **CLAIM**

The ornamental design for a squeeze bottle, as shown and described.

DESCRIPTION

FIG. 1 is a top front perspective view of a squeeze bottle, showing our design;

FIG. 2 is a front elevation view thereof;

FIG. 3 is a right elevation view thereof, with a left elevation view being a mirror image of the right elevation view;

FIG. 4 is a rear elevation view thereof;

FIG. 5 is a top elevation view thereof;

FIG. 6 is a bottom elevation view thereof; and,

FIG. 7 is a top front perspective exploded view thereof.

The broken lines shown in the drawings depict portions of the squeeze bottle that form no part of the claimed design.
